United States Patent Office

Des. 211,757

Patented July 23, 1968

211,757

CONTACT LENS OR SIMILAR ARTICLE

Jacques Urbach, North Hollywood, Calif. (½ Urocon, Inc., 6205 Santa Monica Blvd., Los Angeles, Calif. 90038)

Filed Feb. 13, 1967, Ser. No. 5,790

Term of patent 14 years

(Cl. D57—1)

FIG. 1.

FIG. 2.

FIG. 3.

FIG. 4.

FIG. 5.

FIG. 6.

FIGURE 1 is a front elevational view of a contact lens, showing my new design.

FIG. 2 is an enlarged front elevational view of the contact lens.

FIGS. 3 and 4 are side and rear elevational views respectively thereof.

FIG. 5 is a modified form of the design shown in FIGS. 1 to 4.

FIG. 6 is another modified form of the design shown in FIGS. 1 to 4.

The partially broken line showing the eye of the wearer in FIG. 1 is for illustrative purposes only.

I claim:

The ornamental design for contact lens or similar article, substantially as shown and described.
